UNITED STATES PATENT OFFICE

CHARLES GRANT, JR., OF BOSTON, MASSACHUSETTS.

IMPROVEMENT IN INSOLES FOR BOOTS AND SHOES.

Specification forming part of Letters Patent No. **150,686**, dated May 12, 1874; application filed March 23, 1874.

To all whom it may concern:

Be it known that I, CHARLES GRANT, Jr., Boston, Suffolk county, Massachusetts, have invented certain Improvements in Insoles or False Soles for Boots and Shoes, of which the following is a specification:

This invention relates to a class of insoles or false soles or linings for boots or shoes, composed of two or more laminæ of wood veneer; and consists in applying to one or both sides of each of such laminæ or veneers a sheet of paper for the purpose of protecting the sole against splitting and fracture in wear, and by the action of the sewing-machine.

The drawings accompanying this specification represent, in Figure 1, a perspective view of an insole embodying my improvement. Fig. 2 is a cross-section of the same.

In these drawings, A represents an insole or sole-lining for a boot or shoe composed of several laminæ or veneers of wood. I have found, in practice, that these soles become split and injured to a greater or less extent while being handled and while subjected to wear in a boot; and I also find that they split while being sewed in a sewing-machine. To remedy these objections I apply, by cement or otherwise, to one or both sides of each veneer, a, a sheet of paper, b, as shown by a black

line in the drawings. This paper has the effect of strengthening the wood and binding its grain firmly together, so that no splitting occurs and no abrasion of its edges ensues, while it also enables the sole to be sewed into a boot or shoe as it prevents splitting by the puncture of the needle.

A sole protected or re-enforced as stated may be used as insole for a boot or shoe and secured in place on a McKay sewing-machine, or cable-screw wire, or other machine. It may also be used as a false insole or sole-lining as a substitute for the cork, felt, or other insole now extensively in use. It is warm, dry, and may be rendered water-proof, and has been proved in practice to be very durable.

I claim—

An insole for boots or shoes composed of two or more distinct and separate layers, each consisting of a veneer of wood re-enforced on one or both sides by a sheet of paper united throughout its whole extent with the veneer, said layers when thus formed being united together by sewing, or equivalently, as shown and set forth.

CHAS. GRANT, JR.
